F. E. KERN.
SHAPING AND IRONING TOOL.
APPLICATION FILED FEB. 14, 1921.

Patented May 30, 1922.

INVENTOR
FREDERICK E. KERN
By Edward E. Long, an
ATTY.

UNITED STATES PATENT OFFICE.

FREDERICK E. KERN, OF ST. LOUIS, MISSOURI.

SHAPING AND IRONING TOOL.

1,417,668.

Specification of Letters Patent. Patented May 30, 1922.

Application filed February 14, 1921. Serial No. 444,631.

To all whom it may concern:

Be it known that I, FREDERICK E. KERN, a citizen of the United States, and resident of the city of St. Louis and State of Missouri, have invented certain new and useful Improvements in Shaping and Ironing Tools, of which the following is a specification containing a full, clear, and exact description, reference being had to the accompanying drawings, forming a part hereof.

My invention relates to improvements in shaping and ironing tools, and has for its primary object a tool designed for millinery work, which is provided with a heating unit located in the head so that it will not be necessary to lay the tool aside for heating.

A further object is to construct a shaping and ironing tool which is provided with a portable base into which the tool can be inserted and heated,—the base also serving for holding the tool upright for certain classes of work.

In the drawings:

Fig. 1 is a side elevation of my device.

Fig. 2 is a longitudinal vertical section of the head, supporting rod and base.

Fig. 3 is a vertical section of the heating coil or unit.

In the construction of my device I employ a tool having a head 4. This head is egg-shaped having the end 5 larger than the end 6. This head is provided with a recess 7 in which the heating coil or unit 8 is inserted. The head is also provided with a screw-threaded portion 9, which receives the hollow supporting rod 10. The hollow supporting rod is provided with an enlargement 11 in which is located a portion of the heating coil or unit 8. The hollow supporting rod 10 is also provided with screw threads on its upper end to receive the screw-threaded opening 9 formed in the head. Mounted on the hollow supporting rod 10 is a handle 12, which is provided with an opening 13 and in

the opening 13 is an insulating bushing 14. 45 15 indicates a portable base provided with a tapered opening 16, which is adapted to receive the lower tapered end of the handle 12. This base is adapted to support the tool in a vertical position for certain classes of 50 millinery work and the tool may be readily removed from the base, when desired. 17 indicates the conductor which is in electrical connection with the heating cartridge or unit 8 and passes out through the opening 13 55 in the handle 12 and has attached to one end a plug or socket 18. 19 indicates the conductor leading to the source of electrical energy, which is also provided with the plug 20.

It will be observed from the foregoing description that the heating unit or cartridge 8 not only heats the head 4, but also the enlarged portion of the supporting rod 11.

Having fully described my invention, 65 what I claim is:

1. A shaping and ironing tool comprising an egg-shaped head, a heating coil located in said head, a detachable supporting rod secured to the head, a handle mounted on 70 said supporting rod, a plug carried by the handle, conductors passing through the side of the handle connected to the plug and the heating coil and a detachable base for holding the tool in an upright position. 75

2. A shaping and ironing tool comprising an egg-shaped head, a handle, a supporting rod connecting the head and handle, a heating coil located in the head and supporting rod, a plug carried by the handle, conductors 80 connecting the plug and heating coil, a base provided with a tapered opening adapted to receive the handle mounted on the supporting rod.

In testimony whereof, I have signed my 85 name to this specification.

FREDERICK E. KERN.
